UNITED STATES PATENT OFFICE.

HENRY H. HULSEN AND SHELLEY G. WOODRUFF, OF LOS ANGELES, CALIFORNIA, AS
SIGNORS OF ONE-HALF TO ROTARY DISC BIT COMPANY, OF LOS ANGELES, CALI-
FORNIA, A CORPORATION OF CALIFORNIA.

ROTARY DRILL BIT.

Application filed December 21, 1923. Serial No. 681,945.

Our present invention being referred to as a rotary drill bit, it may be understood to be an object of this invention to provide a drill bit of novel type suitable for use in the drilling of deep wells, such as oil wells.

It is an object of this invention to provide a rotary drill bit of especially rugged and effective construction, comprising a pair of removable blades; and, in a preferred embodiment of our invention, each of the blades referred to may be curved in two planes and provided with means for securing the same to one of two opposite, inner faces of a slot extending through a head provided with means for the secure retention of said blades in their intended relationship, although so constructed as to permit of the ready removal thereof, for purposes of repair or replacement.

It is a further object of our invention to provide a rotary drill bit in the form of a main body comprising a shank threaded at its upper end and provided with a longitudinal circulation channel extending to a slot by which the head of said body may be divided into two substantially identical limbs; and, in a preferred embodiment of our invention the said slot may be provided with upward extensions constituting recesses for the secure retention of the mentioned blades, which may be regarded as counter-sunk therein in such manner as to provide shoulders engaging the inner vertical lateral edges of said blades.

It is a further object of our invention to provide a rotary drill bit comprising removable blades whose inner and upper corners may be substantially rectangular but whose outer corners may be respectively inclined downward in a manner favorable to the efficiency and to the withdrawal thereof, both the bottom edges and the outer edges of the respective blades being preferably forwardly curved, and preferably formed of a tool- or other special steel, each blade being preferably pierced or otherwise provided with a transverse aperture and optionally also with a squared or similar countersink, adapted to receive the head of a bolt. The threaded end of this may be engaged by a nut, for which a corresponding recess may be provided in the edge of a pair of limbs into which the body of a drill bit may be divided by a transverse slot, the

construction of all parts being preferably such as to force the cuttings produced by the rotation of our novel bit inwardly and upwardly and out through the top of the mentioned slot, which may be bevelled in adaptation to the movement referred to.

Other objects of our invention will appear from the following description of a preferred embodiment thereof, alternative types of blades being suggested, and from the appended claims, taken in conjunction with accompanying drawings, in which—

Fig. 1 may be regarded as a side elevation of a drill bit of our improved design,

Fig. 2 being then regarded as a front elevation of the same, and,

Fig. 3 being a vertical section on line 3—3 of Fig. 1.

Fig. 4 is a bottom plan view, having an obvious relationship to the side elevation shown in Fig. 1.

Figs. 5 and 6 are respectively front and edge elevations of an alternative type of blade hereinafter referred to.

Figs. 7 and 8 are respectively side and edge views of an additional alternative type of blade.

Fig. 9 is a horizontal section corresponding to the line 9—9 of Fig. 1 but suggesting the employment of blades unequal in breadth, as hereinafter referred to.

In that specific embodiment of our invention illustrated in Figs. 1, 2, 3 and 4, it will be understood that the main body B of our drill bit comprises a head 1 provided with a transverse slot 2 extending in a vertical plane and through the center of said head, this head being preferably integral with a shank 3, shown as provided at its upper end with a projection 4 carrying a usual tool thread and as provided with a longitudinal central circulation channel 5, through which water or "slush" may be forced.

It being obvious that the slot 2, or its equivalent, divides the head 1 into a pair of symmetrically disposed limbs 1^a and 1^b, we consider it advantageous to secure to the substantially parallel inner faces of these limbs a pair of novel removable blades 6, 6', which may be given any desired specific configuration but which are preferably provided with substantially flat bodies of substantially uniform thickness, and with outwardly and forwardly curved cutting edges.

In the form of our invention shown in Figs. 1, 2, 3, and 4, each of the mentioned blades may comprise a body roughly rectangular in outline, only the inner and upper corner thereof being, however, shown and preserved as a true right angle. It being understood that the lower and outer edges, these being the forwardly curved edges of our novel blades, may advantageously be formed of a tool- or other special steel, and that a downwardly projecting point may advantageously be provided either at the outer lower corner 7 of each blade or at an intermediate point (as suggested in Figs. 5 and 7), we consider it advantageous to retain the respective blades not only by threaded means such as the bolts 8, shown as extending transversely through the said blades and through the corresponding limbs 1^a and 1^b, but also by providing a suitable countersink or depression 9 in each of said limbs, the depth of each depression preferably corresponding to the thickness of the body of the blade to be retained therein, and its outline being such that a blade may closely interfit therewith, the depressions shown in Figs. 1, 3 and 9 being such as to constitute practically upward lateral extensions of the slot 2, lateral shoulders 10 being, however, provided to constitute stops or abutments engaged by the inner and substantially vertical edges of the respective blades. The depressions 9 constitute sockets extending upwardly at the side of the slot 35 and the upper ends of the blades 6 slide up into these sockets so as to assist in firmly holding the blade.

Each blade may not only be cast or tapped for a bolt 8 but also provided with a rectangular or other non-circular countersink 11, adapted to receive the head of the said bolt and to retain the same against rotation; and, in order to prevent damage due to an accidental engagement of a blade with any obstructing object during the withdrawal of a drill bit, we consider it advantageous to bevel or round the upper, outer corner 12 of each blade in a manner best shown in Figs. 3, 5 and 7. For a similar reason, we prefer to provide suitable recesses or countersinks 13 in the outer or rounded surfaces of the respective limbs 1^a and 1^b, to receive the nuts 14 upon the outer or threaded ends of bolts 8.

It should be understood that we may either form the entire blades 6 from a suitable special steel, or we may alternatively form the bodies thereof of a suitable mild or other steel, upon which cutting edges of a preferred harder composition may be welded and renewed from time to time; and we may either employ two substantially identical blades, as indicated in Figs. 1, 2, 3 and 4, or we may employ blades differing in configuration and width, one usual incidental

result of the latter construction being a tendency for our bit to "walk" within a hole. Depending upon the depth at which we may be working, and character of rock encountered, we may alternatively employ either bits with blades having cutting points at the outer lower corners thereof, as shown in Figs. 1, 2 and 3, or bits provided with blades of any suitable alternative design, two alternative configurations being best illustrated respectively in Figs. 5 and 7.

It will be obvious that in the employment of our novel drill bit, "slush" being forced downward through the channel 5 or its equivalent and both the lower edge 13 and the lateral edge 14 of a blade 6 or its equivalent being effective, by reason of the mentioned curvature in the cutting edges thereof, to force loosened material upward and inward within the slot 2; and bevelling of the upper transverse terminal faces 15 of the mentioned slot may be advantageous in feeding cuttings upward and outward to deliver the same from a well hole. It will be noted that the bevelled terminal faces 15 are on each side of a central projection from the head, extending into the slot as shown in Fig. 3 and that the blades engage at their upper edges between the upper part of the limbs and the central projection, therefore forming a rigid locking support for the blades. This detail is brought out in Fig. 1, the tops of the blades being indicated by the dotted line in Fig. 3.

Although we have herein described one complete embodiment of our invention, suggesting various specific alternatives in detail, it should be understood that numerous different modifications might be made without involving a departure from the spirit and scope of our invention and also that various features thereof might be independently employed, the actual scope of our invention being, however, indicated by the following claims:

What we claim is:

1. A drill bit having in combination a main body with a head provided with a transverse slot forming a pair of depending limbs on each side of the slot, a central projection extending downwardly slightly into the slot, a pair of removable cutter blades immovably attached to the limbs of the head with their upper edges engaging the limbs and the downward projection of the head, the blades being secured in a recess in the limbs and having a bearing against a square shoulder formed by the recess.

2. A drill bit comprising in combination a main body having a head at its lower end provided with a transverse slot forming a pair of depending limbs, the faces of the limbs being in substantially parallel planes spaced substantially an equal distance from

- the axial line of the drill, a central projection extending downwardly into the slot from the head and having bevelled transverse terminal faces, a pair of detachable 5 blades secured immovably to the inside faces of the limbs with their upper edges engaging the upper portion of the limbs and the central projection, the blades being secured in a recess in the limbs, said recess having 10 a vertical shoulder adapted to engage the back of the blades and the said limbs having counter-sinks in their outer faces with bolts secured in the counter-sinks clamping the blades.
- 15 3. In a drill bit, a main body having a threaded shank and a head that is divided by a substantially vertical slot forming separate limbs having substantially parallel inner faces, said head being provided with 20 a pair of oppositely extending removable cutter blades oppositely projecting from the said inner faces of said limbs and retained therein by interfitting within recesses terminating laterally in substantially vertical 25 shoulders.
4. In a drill bit, a main body having a threaded shank and a head that is divided
- by a substantially vertical slot forming separate limbs having substantially parallel inner faces, said head being provided with 30 a pair of oppositely extending removable cutter blades oppositely projecting from the said inner faces of said limbs, said blades being substantially right-angled at upper and inner corners thereof and said head being recessed to interfit with said right-angled corner and to provide a vertically extending shoulder constituting an abutment therefor.
5. In a drill bit, a main body having a 40 threaded shank and a head that is divided by a substantially vertical slot forming separate limbs having substantially parallel inner faces, said head being provided with a pair of oppositely extending removable cutter blades oppositely projecting from the said inner faces of said limbs, said blades having cutting edges at unequal distance from the axial center.

In testimony whereof we have signed our 50 names to this specification.

HENRY H. HULSEN.
SHELLEY G. WOODRUFF.
